Fig. 2.

This technical drawing illustrates a mechanical assembly, likely a pump or compressor component. The main body is a rectangular housing with various internal and external parts labeled with numbers. Key components include:

- A large circular part labeled 24, which appears to be a fan or impeller.
- A vertical pipe assembly on the left labeled 40, 38, 31, 21, 32, 30, 29, 33, and 47.
- A horizontal pipe assembly on the right labeled 23, 22, 25, 19, 17, 15, 16, 12, 10, 9, 7, 6, 4, 11, and 1.
- A vertical pipe labeled 5.
- A small rectangular component labeled 4.
- A base or support structure labeled 1.

Dashed lines indicate hidden features and assembly points. The drawing is oriented vertically on the page.

UNITED STATES PATENT OFFICE

GEORGE W. LANGFORD, OF ANN ARBOR, MICHIGAN

BALING PRESS

Application filed April 5, 1923. Serial No. 630,078.

The invention relates to baling presses or like compression devices and refers more particularly to a novel arrangement whereby the plunger is operated at different rates of speeds and the prime mover for operating the plunger is cut out when the plunger reaches either end of its stroke.

In baling presses as heretofore constructed it has been necessary to drive the plunger at a relatively slow speed to secure the desired power for compression, which naturally slows up the work. The present invention has among its objects the provision of a construction in which the plunger has a rate of speed during the latter portion of its compressing movement which is lower than the rate of speed during the first portion of its compressing movement, the rate of speed depending upon the resistance offered by the compressed material. The invention also resides in the provision of an automatic device for shifting the drive mechanism from high speed to low speed; in the provision of an automatic cut-out device for shutting off the power the instant a certain predetermined pressure is exerted on the compressed material; in the provision of an automatic cut-out arrangement for shutting off the power when the plunger is at the outer limit of its stroke; and in the novel features of construction and combinations and arrangements of parts as more fully hereinafter set forth.

In the drawings:

Figure 1 is an end elevation of a baling press embodying my invention;

Figure 2 is a side elevation of a portion thereof;

Figure 3 is a plan view of the drive and control mechanism thereof.

Describing first in detail the general arrangement of the baling press, 1 is the baling chamber mounted on the base 2 and having an open upper end through which the material to be compressed can be fed. 3 is a plunger reciprocable vertically within the baling chamber for compressing the material therein and is actuated by the chains 4 secured to the opposite ends of the plunger. The chains 4 extend over the upper sprocket wheels 5 and the lower sprocket wheels 6

located at opposite ends of the frame for the baling chamber. The lower sprocket wheels 6 are each driven from a gear wheel 7 rotatably mounted on the stub shaft 8 carried upon the base 2 and meshing with a pinion 9 secured upon the shaft 10 extending longitudinally of the base and journaled therein.

The construction is such that with the parts as shown in Figure 1 and when the gear wheels 7 are driven in a counter-clockwise direction, the plunger 3 will be first rocked down onto the top of the material in the baling chamber 1 and then vertically moved downward so as to compress the material in the chamber to a predetermined density. Since the material is naturally fluffy and easily compressed during the first portion of the downward movement of the plunger, I have provided a novel drive mechanism whereby the plunger during this time is moved downwardly at a relatively high rate of speed. When, however, the density of the material is such as to produce a predetermined resistance to the downward movement of the plunger the drive mechanism is shifted so that during the remaining downward movement of the plunger its rate of speed is lower, whereby with the same power the pressure exerted upon the material can be increased. When the material reaches a still further predetermined density the motor or other prime mover is cut out and the plunger is locked in its final position so that the compressed material can be tied if desired, after which the drive mechanism is reversed and the gear wheels 7 are rotated in a clockwise direction to return the plunger 3 upwardly to its open position.

Describing now in detail the drive mechanism, 11 is the worm wheel secured upon one end of the shaft 10 and driven from the worm 12 secured upon the driven shaft 13 extending transversely of and journaled in the base 2. 14 is a drive shaft extending parallel to the driven shaft 13 and also journaled in the base 2. 15 and 16 are respectively a small gear and a large gear secured upon the driven shaft 13, and 17 and 18 are respectively a large gear and a small gear rotatably mounted upon the drive shaft 14.

and meshing respectively with the gears 15 and 16. 19 is a collar splined upon the drive shaft 14 intermediate the gears 17 and 18 and adapted to be longitudinally moved upon this drive shaft into driving engagement with either of the gears 17 and 18. In the present construction the collar has upon its opposite sides driving jaws 20 for meshing with corresponding jaws upon the sides of the gears. The arrangement is such that when the collar 19 is shifted longitudinally upon the drive shaft into driving relation with the gear 17, the latter will drive the gear 15 which in turn drives the driven shaft 13, the worm 12 thereon and the worm wheel 11 meshing with the worm, this worm wheel in turn driving the shaft 10 and the small sprocket wheels 6 through the gear wheels 7 and pinions 9. When the collar 19 is shifted in the opposite direction in driving relation with the gear 18, this gear drives the small sprocket wheels through the gear 16 and the driving elements intermediate the small sprocket wheels and this gear. When the driving is effected through the pair of gears 15 and 17 the small sprocket wheels are rotated at a higher rate of speed than when the driving is effected through the pair of gears 16 and 18.

21 is a hand lever extending upwardly above the frame for the drive mechanism and pivotally mounted at 23 upon the cross bar 22 extending between the side sills of the base 2, the lower end of this hand lever having a fork engaging the collar 19 for shifting the same longitudinally of the drive shaft.

The drive shaft 14 is driven from the electric motor 24 by suitable means such as the chain 25 upon suitable sprocket wheels upon the drive shaft and the motor shaft.

With the arrangement as thus far described and with the plunger 3 in its open position, the first portion of the downward movement of the plunger 3 can be effected at a relatively high rate of speed by shifting the hand lever 21 to the right to bring the collar 19 into driving relation with the gear 17. Then when the material within the bailing chamber reaches a certain degree of compression and consequently offers a certain resistance to the further downward movement of the plunger, the hand lever can be shifted to the left to disengage the collar from driving relation with the high speed driving gear and into driving engagement with the low speed driving gear 18, after which further downward movement of the plunger is effected at a lower rate of speed.

For automatically shifting from high speed to low speed in accordance with the density of the material being compressed or in accordance with the resistance offered by this material, I have provided the following construction: 26 is an upwardly extending lever piv-

oted at 27 upon a side sill of the base and having a bearing 28 located slightly above the pivot 27 for engagement by the adjacent end of the driven shaft 13, which is movable longitudinally in its bearings by the reactive effort of the teeth of the worm wheel 11 meshing with the teeth of the worm 12 secured upon this driven shaft, the degree of reactive effort being dependent upon the degree of compression of the material in the bailing chamber. 29 is an actuating rod extending transversely of the frame of the gear mechanism and longitudinally slidably therein, this rod being connected to the plate 26' secured to the upper end of the lever 26, whereby as the driven shaft 14 is moved longitudinally to the right in Figure 1 and the lever 26 is swung in a clockwise direction, the actuating rod 29 will also be moved to the right. This rod is provided with suitable nuts 30 adjustably threaded engaging the rod and located on opposite sides of one end of the lever 31 pivotally mounted at 32 upon a cross bar 33 of the gear mechanism frame. The other end of the lever 31 is located on the right side of the hand lever 21 (referring to Figure 1), whereby the lever 31 upon being swung by the actuating rod in a counter-clockwise direction will swing the hand lever to disengage the collar 19 from the high speed gear 17 to the low speed gear 18. 30' are coil springs surrounding the actuating rod and abutting the nuts 30 and the opposite sides of the end of the lever 31 therebetween, these springs having sufficient strength to swing the lever 31 to change speeds upon the longitudinal movement of the actuating rod a predetermined distance but allowing subsequent further longitudinal movement thereof. 34 is a coil spring surrounding the actuating rod 29 and abutting the side bar 35 of the gear mechanism frame and the nut 36 adjustably threaded engaging the actuating rod, this coil spring offering a predetermined resistance to the longitudinal movement of the actuating rod and thereby determining the time of shifting the drive mechanism from high speed to low speed. By adjusting the nut 36 upon the actuating rod, compression of the coil spring can be varied to vary the time of shifting.

For the purpose of cutting out the motor when the material within the bailing chamber has reached a final predetermined compression, I have provided means for actuating a suitable electric switch mechanism 37 from the actuating rod 29 when the latter has moved a predetermined distance to the right in Figure 1, this distance being greater than that for shifting from high speed to low speed and this additional movement of the actuating rod being allowed by reason of the coil springs 30'. As shown, this means comprises the horizontal lever 38 pivotally mounted upon the cross bar 30 of the gear mechanism frame and connected to the actuating rod 29

at one end and to the switch lever 39 at the other end. This switch lever is also connected to the hand lever 40 pivotally mounted at its lower end upon the gear mechanism frame 5 and adapted to initially electrically connect the motor 24 to drive the plunger 3 in a downward direction.

Owing to the fact that the drive mechanism includes an irreversible worm driving element, the plunger is automatically held in its final downward position to permit of tying the compressed material, if desired.

41 is a suitable electric switch having the switch lever 42 connected to the hand lever 15 43, which latter is pivotally mounted at its lower end upon the gear mechanism frame. This switch when closed electrically connects the motor 24 to drive the plunger 3 in an upward direction. For cutting out the motor 20 when the plunger has reached its uppermost or open position, there is the pull rod 44 pivotally connected at its upper end to the wheel 45 and at its lower end to the crank 46 journalled in the gear mechanism frame and having an arm 47 engageable with the hand lever to swing the same thereby breaking the electric circuit. The wheel 45 is turned during the final opening movement of the plunger by suitable means, such as an end of the plunger 25 bar engaging a radially extending arm upon the wheel.

What I claim as my invention is:

1. A driving means for baling presses having a baling chamber and a plunger movable therein, including a motor, a worm, change speed gearing between said motor and worm, a worm wheel meshing with said worm and operatively connected to said plunger, a member adapted to be actuated by longitudinal movement of said worm, an actuating rod connected to said member, a lever having one end engaging the actuating rod and the opposite end arranged to control the change speed gearing, and springs 40 upon said actuating rod engageable with said lever and operable upon a longitudinal movement of the worm to control said change speed gearing.

2. A driving means for baling presses having a baling chamber and a plunger movable therein, including a motor, a worm, change speed gearing between said motor and worm, a worm wheel meshing with said worm and operatively connected to said plunger, a longitudinal movable actuating rod adapted to be actuated by longitudinal movement of said worm, a lever operable upon a movement of said rod to shift the change speed gearing, and means for determining the time of shifting the change speed gearing including a spring surrounding said rod and offering a predetermined resistance to the longitudinal movement of the actuating rod.

3. A driving means for baling presses hav-

ing a baling chamber and a plunger movable therein, including power driven means for operating the plunger during the first portion of its movement in one direction at a relatively high rate of speed, and shiftable means responsive to pressure variations in the baling chamber for automatically operating the plunger during a succeeding portion of its movement in the same direction at a lower rate of speed.

4. A driving means for baling presses having a baling chamber and a plunger movable therein, including power driven means for operating the plunger to compress the material within the baling chamber at different rates of speed automatically responsive to the resistance offered by the material being compressed.

5. A driving means for baling presses having a baling chamber and a plunger movable therein, including power driven means for operating the plunger during the first portion of its compressing movement at a relatively high rate of speed and operating the plunger during a succeeding portion of its movement at a slow rate of speed and means for automatically shifting from one speed to the other dependent upon the pressure exerted by the plunger upon the material being compressed.

6. A driving means for baling presses having a baling chamber and a plunger therein, including an electric motor, a worm, change speed gearing between said motor and worm, a worm wheel meshing with said worm and operatively connected to said plunger, an electric motor for cutting out said motor in one extreme position of the plunger, and a common means dependent upon the longitudinal movement of the worm for controlling the said change speed gearing and switch.

7. A driving means for baling presses having a baling chamber and a plunger movable therein, including a motor, a worm, change speed gearing between said motor and worm, a worm wheel meshing with said worm and operatively connected to said plunger, a lever adapted to be actuated by longitudinal movement of said worm, and an actuating rod connected to said lever and controlling said change speed gearing and switch.

8. A driving means for baling presses having a baling chamber and a plunger movable therein including power driven mechanism for operating the plunger during the first portion of its compressing movement at a relatively high rate of speed and for operating the plunger during a succeeding portion of its movement at a comparatively slow rate of speed, and means dependent upon the pressure exerted by the plunger upon the material being compressed for automatically changing from one speed to the other, said

means also operable when the plunger exerts a predetermined pressure upon the material to automatically discontinue the operation of said power driven mechanism to stop further movement of the plunger.

5 In testimony whereof I affix my signature.

GEORGE W. LANGFORD.
